UNITED STATES PATENT OFFICE

HAROLD B. DONLEY, AUGUSTUS J. FRAME, AND JACKSON G. GILMORE, OF COLUMBUS, OHIO, ASSIGNORS TO FRANKLIN OIL HEATING, INCORPORATED, OF COLUMBUS, OHIO, A CORPORATION OF OHIO

OIL-BURNING APPARATUS

Application filed September 4, 1928. Serial No. 303,672.

This invention relates to improvements in oil burning apparatus and in certain of its specific aspects is directed to burner apparatus of the type employed in connection with the heating of buildings, residences and the like. In such apparatus use is made, in certain instances, of equipment comprising a burner structure formed to include an open topped vessel or receptacle into which liquid fuel is introduced and maintained at a predetermined level within the vessel when the apparatus is in active operation, the fuel being suitably mixed with air or oxygen directed to the vessel above the fuel level therefor in for the purpose of producing a highly combustible mixture which will burn both efficiently and economically. In order to supply the vessel with the liquid fuel for the purpose of maintaining such level use is made of an oil line or conduit which enters the vessel in or near the bottom of the latter. Due to the fact that apparatus of this character is intermittently operated, that is, active combustion takes place intermittently, considerable difficulty has been encountered in preventing the accumulation of carbon deposit or carbon encrustations on the walls of the oil conduit immediately adjacent to the zone of entry of such conduit into the vessel. This is due perhaps to the fact that the fuel which remains in the bottom of the vessel following active operation, does not receive sufficient oxygen to support full and complete combustion of the remaining liquid fuel traces in the bottom of the vessel and in the adjacent portions of the oil line. In course of time such carbon deposit obstructs the oil line and prevents the proper and effective use of the apparatus. It is an object of the present invention to provide an auxiliary air duct or supply means leading from the main air duct to the oil line at a point preferably adjacent the pot or retort and certainly closer thereto than to the fuel valve so that during the overrun of the motor after closure of the fuel valve the auxiliary air will function to expel the oil or a large portion thereof in the fuel line adjacent the pot or retort. Having a portion of the auxiliary air duct lo-

cated beneath the oil line provides a species of sump into which any oil remaining in the line near the pot 2 will drain back and be removed from the zone of such heat as would coke or carbonize this residue.

There are several methods of effecting positively the removal of the oil from the oil supply line adjacent the vessel. In the present instance, however, this is accomplished by the provision of an air line which may enter the liquid oil conveying conduit adjacent to the point where the latter enters the burning vessel or combustion pot. The inlet side of the air line communicates with a source of air supply under pressure which consists usually of an air conveying conduit connected with a motor driven fan, said air conduit leading to the combustion vessel or pot so that in operation of the apparatus air under pressure may be intimately mixed for vaporization purposes with the air normally contained in said combustion vessel or pot. By this arrangement when the flow of fuel through the oil line or conduit has been arrested by the main control valve air continues to flow through said air line and into the oil line with the result that the oil accumulations which may be present at the point of entry of the oil line into the combustion pot will be effectively and completely removed so that carbon cannot build up, obstruct the fuel line and interfere with the proper functioning of the system.

With these and other objects in view which will appear as the description proceeds, the invention consists in the novel features of construction, combinations of elements and arrangements of parts hereinafter to be fully described and pointed out in the appended claims.

In the accompanying drawings:

Figure 1 is a view in side elevation of the oil burning apparatus constructed in accordance with the present invention,

Figure 2 is a top plan view of the apparatus set forth in Figure 1,

Figure 3 is a vertical sectional view on a larger scale disclosing more particularly the construction of the combustion pot and the oil and air lines leading thereto,

Figure 4 is a vertical sectional view taken on the line 4—4 of Figure 3.

Figure 5 is an enlarged vertical sectional view of the control valve and its associated mechanism.

The apparatus illustrated comprises broadly a combustion vessel or pot 2, the latter being arranged within the combustion chamber 3 of a furnace or other suitable type of heating unit 4. Leading to the pot 2 is an air conduit 5 which has its outer end disposed in communication with a motor driven fan or blower 6. Also entering the bottom of the vessel or pot 2 is a liquid fuel line or conduit 7, within the air line 5, as shown more particularly in Figures 3 and 4. This fuel line communicates with a main control valve 8, which in this instance is of the magnetically operated type and is disposed within a circuit 9 which includes a source of energy 10 and a thermostatic switch 11. The control valve 8 and switch mechanism, which is disclosed and specifically claimed in the co-pending application, Serial Number 175,293 and therefore not claimed herein consists of a solenoid arranged to open and close a valve opening in the valve body situated in the fuel line 7. The solenoid is also adapted to rock a mercury switch to a circuit opening and closing position for controlling the burner circuit for the motor of the blower 6.

It has been found desirable to maintain the blower 6 in operation for a certain given period after the closing of the fuel control valve, in order that fuel which remains in the pot or burner is permitted to burn off with a sufficient amount of oxygen to support efficient combustion and to prevent a smoky burning condition. This is accomplished by an electrically heated warping bar so positioned with respect to the switch that after the current has been shut off by the thermostat 11, the mercury switch is held in its circuit closing position until the warping bar has cooled and become straightened allowing the switch to rock and open the circuit for the motor, as clearly illustrated by full and dotted lines in Figure 5 of the drawings.

The fuel line 7 is provided with a float 12 by means of which a pre-determined liquid level is maintained within the vessel or pot 2 when the apparatus is in active operation, the float controlling automatically the flow of fuel from a source of supply, such as a tank (not shown).

The vessel or pot is provided with an open top and around the outer and upper portion thereof the said vessel includes an annular flange 13 which is received within a sheet metal casing 14 formed to effect the elevated support of said vessel above the base or floor line. The flange 13 is apertured as at 15 so as to permit of the passage of air therethrough, the casing 14 being in open communication with the inner or discharge end

of the conduit 5 so that air may flow freely under relatively low pressure from said conduit and through the apertures 15 to commingle with the oil vapors released from the oil body which is normally maintained within the vessel 2.

In this instance the vessel 2 includes a vertical and axially upstanding sleeve 16, in the upper end of which is situated an air distributor 17. This distributor comprises a tubular body provided with a head 18 and 75 19 at each end thereof. The lower head 19 is formed with apertures 20 which direct air jets or streams transversely within the vessel 2 for the purpose of effecting a combustible mixture of efficient proportions but to prevent the occurrence of active combustion of the oil within the confines of the vessel or pot. The air released from the apertures provided in the upper head 18 combines with the fuel mixture in a plane above the vessel or pot 2 and likewise so does the air discharged from the apertures 15 of the flange 13. This arrangement provides for the economical and efficient consumption of 85 liquid fuel and produces a system which operates effectively under relatively low air pressures and without atomization of the fuel.

In this instance the bottom of the vessel or pot 2 is provided with an enlargement 21 in which is formed a bore 22, which communicates with the bottom of the pot 2. Entering the outer end of the bore 22 is the forward end of the fuel line or conduit 7. In the form of the invention here depicted, the fuel line 7, intermediate of its length, is provided with a T fitting 23 with which is connected an elbow fitting 24, the latter being connected with an air pipe 25. It will be 105 observed that the outer portion of the air pipe extends in the same general direction and adjacent to the fuel line 7 in a horizontal plane below the line 7, and that the air pipe then terminates in an upwardly and angularly directed portion which enters an inverted U shaped fitting 26, mounted on the top of the air conduit 5. The fitting 26 terminates within the confines of the conduit 5 so that the air flowing through said conduit under the pressure of the blower 6 may enter the pipe line 25 so as to flow into the fuel line 7. It will be observed that the fuel line 7 is slightly inclined in a downward and rearward direction, as shown in Figure 3. Thus when the valve 8 is closed the flow of fuel through the line 7 is completely obstructed. The portion of the fuel in the line 7 beyond the valve 8 and up to the fitting 23 seeks a horizontal level within said fuel line. 110 To take care of the liquid fuel which remains in the line between the fitting 23 and the bottom of the vessel or pot 2 use is made of the air line 25. When the valve 8 is closed the operation of the motor is con- 115 120 125

tinued for a length of time governed by the movement of the warping bar of the controlling switch. If, however, the prolonged operation of the motor is not of sufficient time to allow the burning of all the fuel in the pot and in the pipe line up to the fitting 23 and after the blower has stopped, the air pressure in the air pipe 25 is removed so that the liquid fuel disposed in said fuel line between the fitting 23 and the bottom of the pot 2 may flow back by gravity into the horizontal sump or forward portion of the pipe 25, thus removing all liquid fuel from the zone of entry of the fuel line into the vessel or pot 2, which prevents thereby the formation of free carbon or hardened coke and carbon deposits on the walls of the fuel line entry into the pot, as would be apt to occur if the fuel were not completely and positively removed. Further, during active operation the air from the line 25 flows under pressure through the fuel arranged in the fuel line between the fitting 23 and the enlargement 21. This tends to agitate the fuel and by mechanical action to remove obstructing materials.

It will be noted that we have located the point of entrance of the auxiliary air duct through the oil line 7 at 23 adjacent the pot or retort 2 and much nearer thereto than to the valve 8. This is an important feature of our invention and insures that the resistance to the flow of the air from the auxiliary air duct through the line 7 offered by the oil in the line between 23 and the entrance to the pot 2 will be materially less than that presented by the oil between the point 23 and valve 8. This insures that the auxiliary air will flow through the oil line into the pot 2 rather than backwardly. Since it is inconvenient to supply the valve 8 with a stuffing box or the like due to the resistance which would thereby be offered to its movement, it is highly desirable that the auxiliary air does not function to drive the oil upwardly around the valve stem; hence the advantage of locating the elbow 23 near the pot.

The mercury switch and the warping bar may be omitted from the apparatus when what is called a dry pot is used, that is, only a thin film of fuel spread over the bottom of the burner pot, in which case the motor discontinues its operation together with the shutting off of the valve 8. The fuel which is then contained in the line between the pot and the fitting 23 will flow into the sump immediately upon the stopping of the system.

The sump can, of course, be used with many different arrangements not requiring the employment of the mercury switch for controlling the motor driven blower independent of the operation of the fuel control valve, the first described method of operation being, however, the most desirable.

In view of the foregoing it will be seen that

the present invention provides a simple, efficient and durable burner structure wherein the burner may operate silently and with the use of a simplified mechanical apparatus.

The sustained operation of the burner is insured by the provision of the air line 25 which serves to provide a sump permitting of the positive removal of fuel from the high temperature zone around the point of inlet of the fuel line into the combustion pot. By removing the fuel from this high temperature zone combustion is prevented and the line is kept in a free and open condition.

What is claimed is:

1. Apparatus of the class described comprising a pot, means to supply oil thereto comprising a duct, a valve therefor, air supply means communicating with said pot and including a fan, a motor actuating said fan, means comprising a branch duct connecting said air supply means and said oil duct at a point between the discharge end of the latter and said valve adjacent said discharge end and nearer thereto than to said valve, and means to continue said motor in operation for a desired period of time after the closure of said valve, whereby oil in said duct between the point of connection of said branch duct therewith and said pot will be discharged into said pot.

2. Apparatus of the class described comprising a pot, means to supply oil thereto comprising a duct, a valve therefor, air supply means communicating with said pot and including a fan, a motor actuating said fan, means comprising a branch duct connecting said air supply means and said oil duct at a point between the discharge end of the latter and said valve adjacent said discharge end and nearer thereto than to said valve, and means to continue said motor in operation for a desired period of time after the closure of said valve, whereby oil in said duct between the point of connection of said branch duct therewith and said pot will be discharged into said pot, said branch duct having a portion thereof lower than said fuel duct adjacent its communication therewith whereby oil may drain from said fuel line into said branch duct upon cessation of operation of said fan.

In testimony whereof we affix our signatures.
